[57] CLAIM

The ornamental design for a combined fan housing and hatch cover, as shown and described.

DESCRIPTION

FIG. 1 is a perspective view of a combined fan housing and hatch cover showing my new design attached to the deck of a boat with the hatch cover open, the boat and hatch cover being shown in broken-lines for illustrative purposes only and are not a part of the claimed design;

FIG. 2 is a top plan view thereof;

FIG. 3 is a bottom plan view thereof;

FIG. 4 is a right side view thereof;

FIG. 5 is a left side view thereof;

FIG. 6 is a front elevational view thereof; and,

FIG. 7 is a rear elevational view thereof.
